UNITED STATES PATENT OFFICE.

OTTO T. SCHARMANN, OF MARSHFIELD, WISCONSIN.

WATER-CIRCULATING PUMP FOR COMBUSTION-ENGINES.

1,336,091.

Specification of Letters Patent.

Patented Apr. 6, 1920.

Application filed January 3, 1919. Serial No. 269,544.

To all whom it may concern:

Be it known that I, Otto T. Scharmann, a citizen of the United States, and a resident of Marshfield, county of Wood, and 5 State of Wisconsin, have invented certain new and useful Improvements in Water-Circulating Pumps for Combustion-Engines, of which the following is a specification.

10 My present invention relates generally to water circulating pumps for combustion motors, and more particularly to a specially designed and constructed pump for use in connection with Ford automobiles to replace 15 the thermosiphon action ordinarily present, with a force feed action, and with a minimum disturbance of the parts usually present in connection with the cooling system first named.

20 My invention aims therefore to provide a device of this nature which may be installed with a minimum expense of time, and furthermore aims at the provision of a simple, inexpensive water pump having an effective 25 action and of a durable nature.

In the drawings illustrating my present invention and forming a part of this specification:

Figure 1 is a side elevation illustrating 30 the practical application of my invention; Fig. 2 is a top plan view;

Fig. 3 is a vertical section taken substantially on line 3—3, of Fig. 1;

Fig. 4 is an enlarged horizontal section;

35 Fig. 5 is a vertical longitudinal section taken substantially on line 5—5 of Fig. 4;

Figs. 6 and 7 are vertical cross sections taken respectively on lines 6—6 and 7—7 of Fig. 4.

40 Referring now to these figures, my invention proposes a water pump which includes an elongated frame comprising a bar 10 having at one end an angular arm 11 supporting a shaft bearing 12, and provided 45 at its other end with a pump casing 13 cast integral therewith and projecting laterally therefrom with its axis in the plane of the axis of the bearing 12 and parallel to the axis of the bar 10 or substantially so.

50 The pump casing 13 has a main pumping chamber 14 therein communicating at its forward side with a suction chamber 15, and between the lower portions of these two chambers division wall 16 has a lower opening 17 which as seen in Fig. 5 is on a plane

with the base of the pumping chamber 14 so that when water is withdrawn from the system the pumping chamber will be effectively drained and the danger of freezing avoided.

60 The rear end of the pumping chamber is open and normally closed by a cap plate 18, removal of which permits of ready access to the pumping chamber in order that the same may be cleaned and repaired, and access thus likewise had to the propeller 19 secured by a taper pin 20 upon the rear end of the propeller shaft 21.

Forwardly of this suction chamber 15 the pump casing 13 has a stuffing box 22 through which the shaft 21 projects forwardly through the bearing 12 of the frame arm 11. Secured upon the propeller rearwardly of and in engagement with the bearing 12 is a set collar 23 which, with the 75 propeller 19 properly disposed upon the rear end of the shaft and the rear extremity of the shaft abutting the cap plate 18 as seen in Figs. 4 and 5 in particular, cooperates with these parts in supporting the propeller in exactly the proper relation within the pumping chamber 14.

80 The pumping chamber 14 also communicates at one side with an opening 24 through the frame as seen in Fig. 4, which opens 85 through the bar 10 adjacent one end and is thus adapted for alinement with the water inlet opening 25 of a combustion motor, particularly the engine of Ford automobiles as shown indicated at 26.

90 At opposite sides of the opening 24, the bar 10 is apertured for the reception of bolts 27 by means of which the frame and pump may be secured in position upon the motor, the bolts entering the openings usually 95 present for the reception of the flange bolts of the lower water pipe which, with the present pump, is connected to a downwardly and forwardly extending nipple 28 of the pump casing 13, which communicates at its 100 upper end with the suction space or chamber 15.

105 The forward portion of the propeller shaft 21 extends forwardly beyond the bearing 12 of the frame and is provided with a pulley 29 secured thereon, preferably in the plane of the pulleys 30 and 31 of the crank shaft 32 and fan shaft 33 respectively, so that a single belt 34 as seen in Figs. 1 and 3 may be extended around the three pulleys 29, 30 110

and 31, to drive the propeller shaft 21 of the fan shaft 33 simultaneously from the crank shaft 32.

It is obvious that in the installation of my improved pump, which replaces with that of a positive force feed, the usual thermosiphon cooling system of a Ford automobile, it is simply necessary to remove the flange of the lower water pipe of a Ford 10 motor from the side of the cylinder block and connect my improved pump and its frame in place as described. The lower water pipe is then connected with the nipple 28 after having been cut down sufficiently in 15 length, and the usual fan belt replaced by a belt 34 which will extend around the three pulleys 29, 30 and 31 instead of merely from pulley 30 to 31 as usual.

When so mounted, the pump is ready for 20 operation, and in action sucks water from chamber 15 to chamber 14 of the pump casing and in turn expels such water forcibly into the water space of the cylinder block through the openings 24 and 25.

25 When the water is withdrawn from the cooling system, all water from the pump chamber 14 will drain into the lower water pipe through the opening 17 previously mentioned, and thus avoid all danger of 30 freezing.

The cap 18 on the pump casing, being removable, permits of ready access to the pump chamber and the propeller 19 so that any of the parts may be readily replaced or 35 repaired when occasion arises.

I claim:

1. The combination with a combustion motor having its water jacket provided with a water inlet opening at one side of the cylinder block, of a frame secured horizontally 40 along the cylinder block, having a bearing in its forward end and a pump casing at its rear end, and provided with an opening communicating between the pump casing and the said water inlet opening of the motor, said pump casing having a rear pump chamber and a suction chamber forwardly of the pump chamber, a detachable cap normally 45 closing the rear end of the pump chamber,

a bearing at the forward portion of the 50 pump casing, a shaft extending through the forward bearing of the frame and forwardly through the bearing of the pump casing, a pulley secured upon the forward end of said shaft, said casing having a depending nipple 55 communicating with the suction chamber, a propeller secured upon the rear end of the shaft within the pump chamber, and a belt connecting the pulley of the propeller shaft with the crank shaft and fan shaft pulleys 60 of the motor, the rear end of said propeller shaft extending rearwardly beyond the propeller and into engagement with the cap of the pump casing, and a set collar secured upon the propeller shaft rearwardly of and 65 in engagement with the forward bearing of the frame whereby to prevent endwise movement of the shaft in either direction.

2. A pump attachment of the character described comprising a frame including an 70 elongated bar having an angular arm at one end provided with a bearing, said bar having a pump casing outstanding therefrom at its opposite end provided with an outlet opening through the bar and with an extension 75 nipple forming an inlet, a shaft journaled through the pump casing and through said arm bearing, a propeller secured upon the said shaft within the pump chamber, and a pulley secured upon the outer free end of the 80 propeller shaft, substantially as described.

3. In a device of the character described, a pump casing having a pump chamber and a suction chamber at one side of the pump chamber, a detachable cap normally closing 85 the opposite side of the pump chamber, a shaft journaled axially through the casing, a propeller secured on the shaft within the pump chamber, said casing having a depending nipple communicating with its suction 90 chamber, and also having a division wall across its lower portion between its suction chamber and pump chamber provided with an opening therethrough communicating between the said depending nipple and the 95 lowermost portion of the pump chamber, for the purpose described.

OTTO T. SCHARMANN.
